H. VOLLMER

CARTRIDGE FEED MECHANISM

Filed Aug. 3, 1925.

Fig. 1.

Fig. 2.

Fig. 3.

Inventor:

Henry Vollmer

UNITED STATES PATENT OFFICE.

HEINRICH VOLLMER, OF WURTTEMBERG, GERMANY.

CARTRIDGE-FEED MECHANISM.

Application filed August 3, 1925. Serial No. 47,861.

To all whom it may concern:

Be it known that I, HEINRICH VOLLMER, residing at Wurttemberg, Germany, a citizen of the German Republic, have invented 5 certain new and useful Improvements in Cartridge-Feed Mechanism (for which I have filed the following applications: Germany, May 3, 1924; Sweden, May 17, 1924; Holland, May 19, 1924; Czechoslovakia, May 10 26, 1924), of which the following is a specification.

According to this invention cartridges for machine guns, automatic ordnance and automatic rifles or pistols are expelled by an automatically rotating driver from a magazine which is in cross-section circular but has a gap wherein there is mounted, by means of a suitable bearing, a notched wheel or star-wheel, a portion of which lies within an 15 aperture of the magazine, towards which the cartridges are propelled, so that during rotation of the star wheel the cartridges are received one by one by successive gaps or notches of the wheel, and are delivered to 20 the loading mechanism.

The invention is illustrated in the accompanying drawing, showing an example of the improved mechanism.

Fig. 1 is an end view, and
30 Fig. 2 a side view,

Fig. 3 being a vertical cross-section to a larger scale.

In the drawing *h* designates the magazine, which is a truncated, conical drum with a 35 gap nearly equal to a quadrant of the cone. Within this gap a bearing *b* is fixed to the drum *h* by means of a flange *a*, and in the bearing is mounted a shaft *c* having fixed to 40 it a star-wheel *d*, a portion of which projects into the drum, the latter having an aperture *z* in the gap. The drum *h* is internally about equal in length to the cartridges *p*, which are dropped in loosely, for 45 which purpose the drum has a door not visible in the drawing.

At the center of the drum *h* there is a spindle *e*, on which is mounted a radial cartridge driver plate *k* urged around the spindle, towards the drum aperture *z*, by a powerful

spring *f*, so that it propels the cartridges towards that portion of the star wheel which projects into the drum. The cartridges drop into the notches of the star-wheel, and are carried out of the drum by rotation of the wheel in the direction indicated by the arrow in Fig. 3.

What I claim as my invention and desire to secure by Letters Patent of the United States is:—

1. A cartridge feed mechanism for automatic fire-arms, comprising a cartridge magazine substantially circular in cross-section and having a gap therein substantially equal to a quadrant thereof; said magazine having an aperture opening into said gap; and means projecting through said aperture into the magazine and adapted to discharge the cartridges through the aperture. 60

2. A cartridge feed mechanism for automatic fire-arms, comprising a cartridge magazine substantially circular in cross-section and having a gap therein substantially equal to a quadrant thereof; said magazine having an aperture opening into said gap; and a star-wheel rotatably mounted in said gap 70 and having portions projecting through said aperture into said magazine, said star-wheel being adapted to receive cartridges and to discharge same through the aperture. 75

3. A cartridge feed mechanism for automatic fire-arms, comprising a cartridge magazine substantially circular in cross-section and having a gap therein substantially equal to a quadrant thereof; said magazine having an aperture opening into said gap; a star-wheel rotatably mounted in said gap and having portions projecting through said aperture into the magazine, said star-wheel being adapted to receive cartridges and to discharge same one by one through the aperture; a radially disposed cartridge driver rotatably mounted in said magazine and means for yieldably urging the driver towards said aperture. 80

In witness whereof I have signed this 95 specification.

HEINRICH VOLLMER.
